UNITED STATES PATENT OFFICE.

GEORGE KUGLER, OF CLEVELAND, OHIO.

REMEDIAL APPLIANCE.

SPECIFICATION forming part of Letters Patent No. 349,849, dated September 28, 1886.

Application filed April 7, 1886. Serial No. 198,062. (No model.)

To all whom it may concern:

Be it known that I, GEORGE KUGLER, of Cleveland, in the county of Cuyahoga and State of Ohio, have invented a certain new 5 and Improved Remedial Appliance; and I do hereby declare that the following is a full, clear, and complete description thereof.

This improved article is for the purpose of relief in cases of colic, rheumatism, neuralgia, 10 neurotic affections, and other analogous diseases, and used as hereinafter set forth.

The article is of an oval shape, and curved, forming a chamber between the outside plates, which are attached to a tubular rim. On one 15 or both sides of the case is connected a galvanic battery consisting of a series of plates, (more or less,) the poles of which terminate in the electrodes, which are placed in the hands of the patient or applied to the affected parts of 20 the body.

That the invention may be more fully understood, reference will be had to the following specification and the annexed drawings, making part of the same, in which—

25 Figure 1 is a top view, and Fig. 2 is a longitudinal section in direction of the line *x* *x* in Fig. 1.

Like letters of reference refer to like parts in the several views.

30 The exterior of the appliance consists of two plates, A and B. Between these plates, and around the edges thereof, is soldered a tube, C. This tube is divided into two sections, as indicated by the dividers D D, Fig. 1. Admission to the tubes is through the holes E E, which are provided with screw water-tight caps.

35 Between the two plates A B is a chamber, F, Fig. 2. To one of the plates is attached a screw-cap, G. On the removal of the cap an opening is formed into the chamber F, which is closed on screwing down the cap on packing, to prevent leakage.

On the upper side of the appliance is a series 45 of copper and zinc plates, alternating with interposed suitable material saturated with salt

or acid water. These plates are removable, and are held in position by the screw-cap G, which passes through the pile and holds the plates in contact on the case. The pile is so 50 arranged, and in connection with the wires or poles *a b*, as to induce an electric action, which may be applied to the body by conductors having terminal electrodes. I, however, make no claim to these devices.

The purpose of the tube C is for a receptacle charged with an antiseptic on one side and a medicated preparation on the other section of the tube. One or both sections may be used 55 for this purpose.

The upper parts of the tubes are perforated with small holes to admit of the effluvia from the agents in the tubes to escape. This feature of the invention is of importance in ease the disease gives off an offensive odor, affecting both the patient and those in attendance, when the effluvia from the medicated agent in the tube is also of material aid to the patient. This is attained while the chamber F is charged with warm or hot water and applied to the affected part, as in colic, rheumatism, gaseous distention, and gastralgia, attended by flatulence.

As before stated, the case may be used with hot water, with or without the appendages described.

What I claim as my invention, and desire to secure by Letters Patent, is—

The chambered case having a tubular attachment between the plates of the case around 80 the edges thereof, and provided with screw-caps E and G, for admission to the chamber and interior of the tube, said tube having perforations therein, arranged substantially as described, and for the purpose set forth.

85 In testimony whereof I affix my signature in presence of two witnesses.

GEORGE KUGLER.
